UNITED STATES PATENT OFFICE.

MEINHARD WITTE, OF MINNEAPOLIS, MINNESOTA.

RADIATOR-FIN-FORMING MACHINE.

Application filed August 20, 1923. Serial No. 658,234.

To all whom it may concern:

Be it known that I, MEINHARD WITTE, a citizen of the United States, residing at Minneapolis, in the county of Hennepin and State of Minnesota, have invented certain new and useful Improvements in Radiator Fin-Forming Machines; and I do hereby declare the following to be a full, clear, and exact description of the invention, such as will enable others skilled in the art to which it appertains to make and use the same.

My present invention relates to machines for forming radiator core fins out of thin sheet metal ribbons or strips and is particularly designed as an improvement on or addition to the machine for the above purpose disclosed and claimed in my U. S. Letters Patent entitled "Radiator fin forming machine," No. 1,484,600, issued Feb. 20, 1924.

In my said prior machine and the present machine, there is a corrugating mechanism and a punching mechanism, the latter receiving from the former. In the prior machine, however, the corrugated ribbon was intermittently fed to the punching mechanism by a manually operated feed device requiring an attendant to manipulate the same. My present invention is directed to an automatic ribbon-feeding device that is operated intermittently to feed the corrugated ribbon from the corrugating mechanism to the punching mechanism and is operated with a properly timed action in respect to both of said mechanisms. This automatic feed device eliminates the necessity of an attendant and, hence, is an important labor-saving device.

In the accompanying drawings, which illustrate the invention, like characters indicate like parts throughout the several views.

Referring to the drawings:

Figure 1 is a side elevation showing the ribbon-corrugating mechanism, a portion of the ribbon-punching mechanism and the automatic ribbon-feeding device operatively associated with said two mechanisms;

Fig. 2 is a fragmentary plan view showing a portion of the ribbon-corrugating mechanism and a portion of the ribbon-feeding device;

Fig. 3 is a fragmentary vertical section showing the ribbon-feeding cross head, feed dog and immediately associated parts;

Fig. 4 is a detail in transverse vertical section on the line 4-4 of Fig. 1; and Fig. 5 is a section taken approximately on the irregular line 5-5 of Fig. 4, some parts being shown in full and some parts being broken away.

In Fig. 1, the ribbon-corrugating mechanism is indicated as an entirety by the character A and the punching mechanism by the character B. Inasmuch as both of these mechanisms are clearly described in detail in my said prior patent, the parts thereof may be here briefly designated as follows: Of the parts of the ribbon-corrugating mechanism, in so far as it is desirable to note the same, the numeral 6 indicates a spool for holding the fin-forming brass ribbon γ . This spool is supported by arms 7 of a supporting frame 8. From the spool, the ribbon is passed between upper and lower forming rollers 9 and a pair of corrugating rollers 10 suitably journaled in laterally spaced bearing plates 11 rigidly secured on the top of the frame 8. The lower rollers 9 and 10 are driven through intermeshing gears 12. The shaft of the lower corrugating roller 10 is provided at one projecting end with a bevel gear 13 and at its other projecting end with a spur pinion 14. As shown, the bevel gear 13 meshes with a bevel gear 15 carried by a driving shaft 16 journaled in a bearing bracket 17 on the frame 8 and provided with a fixed pulley 18 and a loose pulley 19, over which a power-driven belt, not shown, will run to drive the rollers of the ribbon-forming and corrugating mechanism.

Rigidly secured on a suitable frame 20 is a horizontal bed plate 21 on which is secured a punch-equipped plate 22. The numeral 23 indicates a vertically movable punch head located above the punch plate 22 and held for vertical movements by guideways 24 formed on the upper portion 20^a of the frame 20. This punch head 23 is adapted to be given vertical movements by any suitable means, such as usually found in punching machines, and for the purpose of this case it is only desirable to note the links 25 that connect said head to eccentrics 26 carried by an eccentric or crank shaft 27 mounted in said upper frame portion 20^a.

A heavy driving pulley 28 is loosely journaled on the projecting end of the crank shaft 27, and, adjacent to the hub thereof,

said shaft is provided with a clutch hub 29 formed with a large segmental notch 30. The hub of the pulley 28 is provided with at least one and as shown two laterally 5 spring-pressed clutch dogs 31 shown as elongated metal blocks set into counter sunk seats in the hub of said pulley and adapted, when released, to enter the notch 30 of the clutch hub 29 and thereby connect the driving shaft 27 to said driving pulley. The elements 29 and 31 constitute elements of a one-revolution clutch, which, so far as this invention is concerned, may take various forms but which, as illustrated, comprises 10 also the following elements: Mounted for radial sliding movements in the hub of the pulley 28 for cooperation one with each of the clutch dogs 31, are clutch dog latches 32, which, in themselves, are in the nature 15 of secondary dogs and are spring-pressed radially toward the axis of the shaft 27 and normally engage notches in the cooperating clutch dogs 31, so that the latter will be held retracted and out of engagement with 20 the clutch hub 29, thereby leaving the shaft 27 normally at rest while the pulley 28 continuously rotates. The latches 32 are provided with outstanding cam lugs 33 for a purpose which will presently appear. 25

The numeral 34 indicates a clutch-tripping lever pivoted to the upper frame structure 20^a at 35 and, at its free end, upwardly spring-pressed by a coiled spring 36 that is subject to an adjusting screw 37. At its 30 free end, the lever 34 is formed with an outstanding segmental latch-tripping flange 38 and with a segmental clutch dog retracting cam 39 that is beveled in respect to a plane to which the axis of the shaft 27 stands at 35 a right angle. At its intermediate portion, the lever 34 is provided with a notch 40, the purpose of which will presently appear. 40

The ribbon-feeding mechanism comprises a cross-head 41 mounted to slide on horizontal guide bars 42 rigidly secured to and projecting from the bed plate 21. The corrugated ribbon *y* is passed through a guide passage 43 of the cross-head 41 and, above said passage, said cross-head is provided 45 with a spring-pressed driving dog 44 that is yieldingly pressed into engagement with the corrugations of the ribbon *y*. This dog will positively engage the corrugations of the ribbon *y* and cause the same to move 50 with said cross-head when the latter is moved from the right toward the left or toward the punching mechanism, but said dog will slip freely over the ribbon when 55 said cross-head is moved in a reverse direction or in a direction away from the punching mechanism. 60

The numeral 45 indicates a long lever that is intermediately pivoted to a fixed bearing 46 and at its left-hand is connected 65 by an adjustable rod or link 47 to the free

end of an intermediate lever 48. The free end of said lever 48 is spring-drawn upward to the position in Fig. 4, by a coiled spring 49. The intermediate portion of the lever 48 is adjustably pivoted at 50 to the lower end of a 70 tripping bar 51 that is guided for vertical sliding movements and permitted a slight oscillatory movement by guide lugs 52 on the upper frame portion 20^a. The upper portion of the trip bar 51 is bifurcated so 75 that it freely straddles the intermediate portion of the clutch-tripping lever 34 and, at the upper portion of the slot formed by its bifurcation, said bar is provided with a bearing lug 53 that normally rests on the 80 upper edge of the lever 34 but is adapted to be dropped into the notch 40 of said lever. Also at its free upper end, the bar 51 is provided with a laterally offset surface 54 that is adapted to be engaged by 85 outwardly projecting portions of the clutch dogs 31, all as will presently appear. 90

The right-hand end of the main lever 45 overlies and is subject to a segmental cam 55 (see Figs. 1 and 2) that is carried by a short shaft 56 journaled in the lower end of a supporting bar 57 that is rigidly secured and depends from one of the bearing plates 11. On the outer end of the shaft 56, by means of a nut or other suitable device, is rigidly but detachably secured a spur gear 58, which, by two intermediate gears 59 and 60 journaled to said bar, is connected to a spur gear 61 journaled to the upper portion 100 of said bar 57. The gear 61, by a small gear or pinion 62, is connected to the spur pinion 14 carried by the shaft of the roller 10. Preferably, and as shown, the pinion 62 is slidably mounted on a fixed spindle 63 that projects outward from the adjacent frame plate 11 so that said pinion may be moved into and out of mesh with the pinion 14 and gear 61. All of the gear elements 59, 60, 61 and 62 operate as intermediate gears between the pinion 14 and gear 58. Obviously, with the arrangement just described, the cam 55 will be rotated at a much slower speed than the pinion 14. 105

The segmental cam 55, as shown, is formed on one side of a larger crank disk 64 having 110 a wrist pin 65.

Pivoted at its lower end to the fixed bearing 46 is an upstanding strip-feeding lever 66, the upper end of which is connected by a longitudinally adjustable link 67 to a lug 68 on the bottom of the cross-head 41. The link 67 is shown as made adjustable by providing its overlapped strip members with longitudinally spaced perforations through which a pin or small bolt 69 is adapted to be passed. 120

Slidably mounted on the intermediate portion of the lever 66 is a collar 70 that is adapted to be rigidly secured in any desired adjustment by a set screw 71. The collar 70 130

is connected to the wrist pin 65 of the crank disk 64 by a link or connecting rod made up of a tubular member 72 and a telescoped rod 72^a, which elements are adapted to be rigidly connected together in different longitudinal adjustments by a set screw 73.

In practice, the corrugated ribbon γ will be permitted to sag or loop down a very considerable distance toward or even onto the floor, so that the slack will never be entirely taken up under the intermittent feeding action of the cross-head, and to guide the same the corrugating mechanism at the delivery end of its frame is shown as provided with a curved guide plate 74, and the cross-head guide 42 at its receiving end is provided with a similar downwardly curved guide plate 75.

When the corrugating and punching mechanisms are in operation, the action of the feed device will be substantially as follows:

The corrugated strip γ will be delivered from the corrugating mechanism in an evenly flowing stream, and while the ribbon is being punched, the slack portion of the ribbon will drop down between the two mechanisms. In Fig. 1 the cross-head 41 is at the right or in its extreme retracted position but will receive its inward or strip-feeding movement during the next 180° of movement of the gear 58, cam 55 and crank disk 64. During the next 180° of rotation of said parts, the cross-head will be given its return or idle movement; and it is during the time that this return movement takes place that the cam 55, acting on the main lever 45 and the connections described, draws downward the tripping bar 51. When the bar 51 is thus drawn down, its bearing lug 53 will force downward the free end of the clutch-tripping lever 34, and the first effect of this is to cause the flange 38 of said lever to come in the path of movement of the lug 33 of the first latch 32 that happens to pass the same, and by this engagement the said latch will be moved radially outward, thereby releasing the cooperating clutch dog 31 and permitting the same to move into the notch 30 of the clutch hub 29. This, of course, connects the crank shaft 27 to the driving pulley or wheel 28 and produces one complete rotation of said shaft, which results in one downward and return movement of the punch head 23. Shortly after the clutch dog engaged the notch 30 of the clutch hub 29 and started the rotation of the shaft 27, the radially outward portion of the operative dog 31 came into engagement with the flange 54 of the trip bar 51, thereby oscillating said bar to the position indicated by dotted lines in Fig. 4 and thereby aligning the lug 53 with the notch 40 and permitting the lever 34 to immediately return to its

normal position shown in Fig. 4, in which position its cam surface 39 will stand in the path of movement of the outer portion of the operative dog 31 and will cam said dog back to its normal position upon the completion of one complete rotation of the shaft 27. When the operative dog 31 is thus forced back to its normal position shown in Fig. 5, its cooperating latch 32 will again engage and retain the same in such inoperative position until another tripping action has taken place. Of course, one clutch dog 31 would be operative, but the two clutch dogs cause the clutch mechanism to go into action almost instantly, regardless of the rotary position of the driving wheel 28 at the time the tripping action takes place.

By longitudinal adjustments of the link 67, or by longitudinal adjustments of the links 72-72^a, or by adjustments of both thereof, the cross-head can be set so that it will start from just the proper outward position, and by adjustments of the collar 70 on the oscillatory lever 66, the length of stroke imparted to the cross-head may be varied. The first noted adjustments are for the proper delivery of the strip between the elements of the punch, and the latter noted adjustment sets the feeding device to feed just the proper length of corrugated ribbon for each feed movement.

As illustrated, the machine may be assumed to be designed to feed an eighteen-inch length of corrugated fin strip, such as required in Ford radiators, and, hence, the feed device should be adjusted to feed eighteen inches of corrugated ribbon for each feed movement.

When the machine is to be used for a considerable length of time to feed longer ribbon strips, then the corrugating mechanism should be set to corrugate correspondingly longer portions for each rotation of the cam 55 and parts connected to rotate therewith. Nevertheless, in practice it has been found perfectly feasible to set the cross-head for feed movements exceeding the amount of corrugated ribbon turned out by the corrugating mechanism, but such use requires that a large amount of slack be maintained in the ribbon between the corrugating mechanism and the punching mechanism and, moreover, it will require that occasionally the ribbon-feeding mechanism be thrown out of action so as to produce the required excessive slack in the ribbon between the corrugating mechanism and the punching mechanism. This may be easily done simply by temporarily sliding the intermediate pinion 62 on its spindle 63 out of mesh with the driving pinion 14 and intermediate gear 61. It will be understood and further noted by reference to my said prior patent, that the punching mechanism also includes a shearing device for cutting off in proper

lengths the corrugated ribbon after it has been punched.

What I claim is:

1. The combination with ribbon-corrugating mechanism and ribbon-punching mechanism, the latter receiving the corrugated ribbon from the former, of a ribbon-feeding device operative on the corrugated ribbon between the said two mechanisms and timed in respect to said corrugating mechanism, and means controlled by said feeding device for intermittently tripping the punching mechanism into action.
2. The combination with ribbon-corrugating mechanism and ribbon-punching mechanism, the latter receiving the corrugated ribbon from the former, of a ribbon-feeding device operative on the corrugated ribbon between the said two mechanisms and timed in respect to said corrugating mechanism, said punching mechanism including a one-revolution clutch through which it is driven, and in further combination with a clutch-tripping device intermittently operated by said feeding device.
3. A ribbon-corrugating mechanism including a pair of ribbon-corrugating rollers, a crank and a cam driven from said corrugating rollers, in combination with ribbon-punching mechanism, means including a one-revolution clutch for driving the ribbon-punching mechanism, and in further combination with a ribbon-feeding device

comprising a cross-head guide leading to 35 said punching mechanism, a cross-head mounted on said guide and provided with a ribbon-feeding ratchet-acting dog, an oscillatory lever, a link connecting said lever to said cross-head, a link connecting said lever to said crank, and a lever subject to said cam and having a connection for tripping the one-revolution clutch of said punching mechanism intermittently into action.

4. The structure defined in claim 3, in which the link connection between said crank and oscillating lever is slidably adjustable on the latter to vary the feed movement of said cross-head.

5. The structure defined in claim 3, in which the link connection between said oscillatory lever and crank is longitudinally adjustable.

6. The structure defined in claim 3, in which the link connection between said oscillatory lever and crank is longitudinally adjustable and is adjustable on said oscillatory lever to vary the feed movement of said cross-head.

7. The structure defined in claim 3, in which the link connection between the oscillatory lever and cross-head is longitudinally adjustable.

In testimony whereof I affix my signature.

MEINHARD WITTE.
